UNITED STATES PATENT OFFICE.

THOMAS MORRIS DAVIES, OF LLANELLY, WALES.

TIRE-INFLATING PUMP.

1,377,563.

Specification of Letters Patent. Patented May 10, 1921.

Application filed September 21, 1920. Serial No. 411,759.

To all whom it may concern:

Be it known that I, THOMAS MORRIS DAVIES, a subject of the King of Great Britain, residing at Llanelli, in the county 5 of Carmarthen, Wales, have invented a new and useful Tire-Inflating Pump, of which the following is a specification.

The invention relates to that type of pump in which the barrel is pivoted at its 10 lower end upon a base and in which the base is provided with a vertical standard or support which is gripped at its upper end by one hand, the hand lever for operating the pump being pivoted to the upper 15 end of the standard or support and being pivoted to the pump rod intermediate of its ends. In such pumps the base has hitherto extended on the same side of the standard or support as the hand lever or else the 20 base has been quite narrow and has extended on either side of the standard or support. In this latter type of pump it has been proposed to rock the standard in the act of pumping.

25 The object of the present invention is to improve this type of pump so that a longer stroke of the hand lever may be obtained without unduly stooping and so that the hand lever assumes a better position for 30 effective work especially toward the end of the stroke when most power is required.

According to the present invention the 35 base extends to a considerable extent on the opposite side of the standard to that on which the hand lever is located and the standard and base are rocked, in the act of pumping, on the outer end of the base. The base therefore becomes more and more vertical as the stroke of the pump progresses 40 until it is almost or completely vertical at the end of the stroke, thereby raising the lower end of the pump barrel to an extent approximately equal to the length of the base. Then as the hand lever is raised to 45 draw air into the pump barrel the base returns to its original horizontal position lowering the pump, consequently the outer end of the hand lever is brought into a convenient position at the commencement of the 50 stroke.

The hand lever as heretofore is pivoted intermediate of its ends to the pump rod and the upper end is in alinement with the

pump rod at the lower end of the stroke. From the point where it is pivoted to the 55 pump rod, the hand lever is bent outward for a short distance only and is then bent parallel or approximately parallel to the upper part thereof so that the outer end of the hand lever is parallel or approximately 60 parallel to the pump barrel at the lower end of the stroke. This method of bending the hand lever brings its outer end lower at the commencement of the stroke than in previous constructions and brings it horizontal or approximately horizontal at the 65 end of the stroke and in a good position to apply the weight of the body in driving the compressed air out of the pump. Owing however to the base being approximately 70 vertical at this time the hand lever is well raised above the ground.

The invention is illustrated in the accompanying drawings in which Figure 1 is a side elevation of a pump and Fig. 2 is a 75 front elevation of the same partly in section.

Fig. 3 is a side elevation, Fig. 4 is a plan and Fig. 5 is a front elevation of the lower part of a pump showing a modification, Fig. 6 is a cross section to an enlarged scale 80 on the line 6-6 of Fig. 3. Fig. 7 is a side elevation showing the base and stay rods folded.

Fig. 8 is a side elevation and Fig. 9 is a plan showing a further modification. 85

In the construction shown in Figs. 1 to 7 a a are strips of metal connected together at their upper and lower ends thus forming a standard. At their upper ends they carry a knob a¹ to be gripped with one hand and 90 at their lower ends they are mounted on a pair of feet a². In Figs. 1 and 2 the knob a¹ is shown in full lines at the extreme top of the standard a a. If desired the knob may be arranged slightly lower and at the 95 side of the standard as shown in dotted lines at a¹⁰ in two places. By thus lowering the position of the knob the pump is rendered more suitable for short persons. The knobs a¹ or a¹⁰ are preferably mounted 100 loosely on a central spindle a³ so that they may rotate in the act of pumping. If the knobs be fixtures on the standard a a they must slip within the hand in the act of pumping.

The base consists of two parallel members

b b connected at their outer ends at *b*¹. These three parts are made from a single strip of metal fixed at *b*² to the standard *a a*. The members *b b* are connected by stay rods *b*³ *b*³ to the standard *a a* at *b*⁵. The base is provided at its outer end with feet *b*⁴. The parts *b* and *b*³ may be pivoted to the standard *a* at *b*² and *b*⁵ and they may be connected together by means of thumb screws *b*⁶ thus enabling the parts to be folded as shown in Fig. 7. The stay rods *b*³ *b*³ are preferably connected by a cross rod *b*⁷ curved at its center to fit the pump barrel when the parts are folded. This cross rod *b*⁷ supports the flexible air delivery pipe *f* when this latter is not supported by the clip *f*¹ and prevents the tube *f* being bent sharply at its lowest end.

c is the pump barrel pivoted at *c*¹ to a cross piece *c*² fixed to the lower part of the standard *a a*.

d d is the hand lever pivoted at one end at *d*² to the standard *a, a* and pivoted intermediate of its ends at *d*³ to the pump rod *c*³. The hand lever has a portion *d* which is in alignment with the pump rod *c*³ at the end of the downward stroke of this latter. The hand lever is then curved outward from the point *d*³ where it is pivoted to the pump rod *c*³ and its outer or handle end *d*⁴ is bent so that it is nearly parallel the pump barrel *c* at the end of its downward stroke. This form of hand lever prevents the outer end thereof being unduly raised at the commencement of the pressure stroke.

e is the usual pressure gage, and *g* is a stop to limit the motion of the hand lever at the end of the pressure stroke.

*b*⁸ is a foot standing outward from the base to prevent the pump falling over toward the hand lever *d d*¹ if this latter be raised without gripping one of the knobs *a*¹ or *a*¹⁰. The foot *b*⁸ standing out beyond the pressure gage *e* also to some extent protects the latter.

In use the pump is rocked on the feet *b*⁴. At the right side of Fig. 1 the hand lever *d d*¹, the pump rod *c*³ and the pump barrel *c* are shown in the position they assume at the commencement of the pressure stroke. As the hand lever *d d*¹ is depressed the knob *a*¹ or *a*¹⁰ is moved to the left in the direction of the arrow and the whole apparatus rocks on the feet *b*⁴. At the left side of Fig. 1 the parts are shown in the position they assume about half way through the pressure stroke. The parts are rocked still further around the point where the feet *b*⁴ rest on the ground, toward the end of the stroke, so that the members *b b* assume a more vertical position at the end of the pressure stroke.

This rocking of the parts prevents the outer end *d*¹ of the hand lever being unduly raised at the commencement of the pressure

stroke and it prevents the hand lever being unduly depressed at the end of the said stroke notwithstanding that the movement of the hand lever is considerable.

In the construction shown in Figs. 1 and 2 the base has a fixed length but it may be desirable to make the length of the base adjustable thereby enabling the lower part of the pump barrel and consequently the hand lever to be adjusted with respect to the ground at the end of the pressure stroke to suit people of various heights. Such an adjustable base is shown in Figs. 3 to 6. The side members *b b* and the stays *b*³ are similar to those shown in Figs. 1 and 2 except that the lower ends of the stays in Figs. 3 to 5 are located within the members *b b* instead of on the outside as in Figs. 1 and 2. On the members *b b* is mounted a sliding extension consisting of side members *B B* and a connection *B*¹. To this latter are fixed the feet *b*⁴ upon which the whole apparatus rocks in the act of pumping as previously described. The side members *B, B* have slides *B*² which partly surround the side members *b b* and slide thereon. The side members *B, B* and *b, b* are both provided with perforations *B*³ and pins *B*⁴ are passed through corresponding perforations thereby retaining the sliding members *B B* fixed on the other members *b, b*.

In the modification shown in Figs. 8 and 9 the base, instead of rocking on feet on the ground, is pivoted to a base board *h* and the feet *a*² instead of standing on the ground stand on said base board *h*.

The base board *h* has a block *i* mounted on a vertical pivot *i*¹ carried by the base board *h*. To this block *i* are horizontally pivoted at *i*² the side members *b b* of the base. This construction allows the whole apparatus to be turned on the vertical pivot *i*¹ into the position shown in Fig. 9 when a foot may be placed on the base board *h* to keep the same steady.

To the sides of the base board *h* are attached spring clips *j j* which spring over the feet *a*² when these latter are standing on the base board *h*. The feet *a*² may easily be forced down into position between the spring clips *j j* or they may be pulled up from beneath the clips *j j* as these latter are carried by long springs *j*¹ *j*¹.

The pump is used exactly as described with respect to Figs. 1 and 2 as the whole apparatus can rock on the pivots at *i*². Corresponding parts of Figs. 1 and 2 and of Figs. 8 and 9 are marked with corresponding letters of reference.

What I claim as my invention is:—

1. An air pump having in combination a standard, a handle at the upper end of the standard, a pump barrel pivoted near to the lower end of the standard, a hand lever pivoted near to the upper end of the stand-

to the pump rod, said handle extending and operating on one side of the standard, a base pivoted to said standard and extending substantially on the opposite side of the standard to that on which the hand lever extends, a base board, a block vertically pivoted to the base board and to which block

the base is pivoted at its outer end, feet on the lower end of the standard and clips carried by the base board beneath which the feet engage substantially as set forth.

5 In witness whereof I have set my hand.

THOMAS MORRIS DAVIES.
